REVERSIBLE SWITCH POINT GUARD

Original Filed Nov. 30, 1929

UNITED STATES PATENT OFFICE

LYLE H. FULTON, OF NASHVILLE, TENNESSEE, ASSIGNOR TO RAIL APPLIANCE CORPORATION, OF NASHVILLE, TENNESSEE, A CORPORATION OF TENNESSEE

REVERSIBLE SWITCH POINT GUARD

Application filed November 30, 1929, Serial No. 410,792. Renewed July 21, 1931.

This invention relates to guards applied to the rail of a track in front of a switch point, the guard acting to shift the wheel inward a slight degree to prevent the flange of the rail from splitting the switch and the invention particularly relates to certain improvements in the switch point protector which forms the subject-matter of Patent 1,649,954 granted to me on November 22, 1927.

Generally speaking, the present invention has for its objects to reduce the cost of the protector, to increase its life, and facilitate replacement when necessary and more particularly it has for one of its objects, the formation of the guard in two sections, one of these sections constituting a blade or head piece and the other section constituting a block supporting the wear piece or blade in proper relation to the head of the rail, thus permitting the head piece or blade to be made of relatively expensive material, while the supporting block may be made of cheaper material, this construction permitting the head piece or blade to be replaced when necessary without requiring the replacement of the entire guard.

A further object in this connection is to provide a head piece or blade which is double so that when one portion of the blade or head piece has been worn to an undue extent, the head piece may be reversed to support an unworn portion in conjunction with the rail head, thus doubling the life of this blade or head piece.

Another object is to so form the supporting or wedge block and the head piece that they may be wedged between the base of the rail and the head of the rail and will be held in place by this wedging action even though the bolt which is ordinarily used for holding the wedge block in place and forcing it inward be accidentally broken or loosened.

Another object is to so engage the head piece with the wedge block that there can be no lateral shifting of the head piece relative to the wedge block.

Other objects will appear in the course of the following description.

My invention is illustrated in the accompanying drawings, wherein:—

Figure 1 is a side elevation of a main rail and a portion of the switch point with my guard applied thereto; 55

Figure 2 is a top plan view of the main rail switch point and guard, as shown in Figure 1;

Figure 3 is a section on the line 3—3 of Figure 1; 60

In these drawings, A designates the main rail, a the head of the main rail and b the base or flange of the main rail. The switch point is designated C. My improved guard is disposed in advance of the switch point. 65 The guard consists of a wedge block or supporting block designated 10 and the head piece which is designated 14. The block 10 has a thickness less than the distance from the outside face of the head a to the web of 70 the rail or the width of the flange b.

The under face of the member 10 is beveled as at 11 to fit against the beveled face of the flange b. The upper face of this block is likewise beveled as at 12 downwardly and inwardly. This upper face is preferably provided at spaced points with the upwardly projecting triangular transversely extending teeth 13 which fit in notches 13^a formed in the head piece 14. 75

The wedge block 10 or supporting block is preferably formed of malleable iron and may have any desired length but preferably in actual practice will be made from four to six inches long. 80

The head piece 14 is formed to fit upon the upper beveled face 12 of the wedge block 10 and in cross section is so formed as to provide the reversely directed offset portions or blades 15, the inner faces of these blades 15 being so formed at 16 as to fit closely against the edge face of the rail head a. Each portion 15 of the head piece 14, as indicated in Figure 2, has its upper edge beveled or tapered toward the ends. Thus the upper edge of each portion 14 is relatively thin and straight. In vertical section, each blade 15 extends downward and outward in a curve as shown in Figure 3, but this blade 15 becomes more and more tapered longitudinally as it nears the 95 100

edge of the blade so that each blade 15 when in place acts to gently wedge against the flange of the rail and force the wheel gently inward so as to carry the flange beyond the outer face of the switch point C. As shown in Figure 3, the blade 15 which is uppermost, fits as at 16 snugly against the inside face of the head a of the rail while the blade 15 which is extended downward fits closely against and conforms to the beveled upper edge of the wedge block 10 as at 17, and the inner surface of this wedge block as at 19.

The middle of each blade 15 is cut away as at 18 so that that blade 15 which is downward will accommodate the bolt 20. In order to dispose the blade 15 of the head piece 14 in proper relation to the rail to cause it to bear against the upwardly beveled or rounded face of the rail, it is necessary that the inner face of the wedge block 10 be recessed as at 19, this recess extending downward and inward to a slight depth and then extending outward to the inner face of the wedge block, as shown in Figure 3, this recess 19, of course, extending the full length of the wedge block. It will be understood, of course, that each edge face 17 of each blade is notched as at 18 to receive the corresponding tongue 13 on the wedge block.

Extending through the wedge block 10 and through the web of the rail is a bolt 20, the shank of this bolt having a somewhat elliptical portion 21 adjacent its head. This elliptical portion fits within a vertically elongated opening 22 formed in the wedge block 10 so that the bolt is held from rotation. The bolt passes through a washer 23 whose lower edge face fits against the base of the rail so that the washer cannot turn. Between the nut 24 and this washer 23 is disposed a split resilient lock washer 25.

The head piece 14 is preferably made out of manganese steel which, of course, has wearing qualities, but is relatively expensive while the wedge block 10 is preferably made out of malleable iron, thus greatly reducing the cost of the protector as a whole. When disposed for service, the blade 15 which is against the head of the rail diverts the railway wheel away from the tapering switch point and thus prolongs the life of the switch point and when one blade 15 is worn out, the other blade may be disposed for service by merely loosening the bolt 20 and reversing the blade without the necessity of removing the bolt or entirely removing the wedge block.

The head piece 14 depends, for its main support, upon the wedging action of the wedge block 10 wedging against the base of the rail A and against the under side of the head piece. Pressure against the outer surface of the blade 15 will only act to wedge the two parts 14 and 10 more firmly in place. As the nut 24 is tightened, the wedge block slides inward, exerting a wedging action

against the head piece, urging it upward tightly against the rail head and wedging it in place against this head and in actual practice it has been found that the wedge block and the head piece will remain in place and will carry out their functions even though the bolt be broken or even entirely removed.

It will be seen that there is a space between the wedge block and the face of the web so that the wedge block may move inward and that there is a slight space between the upper corner of the depending blade 15 and the web which permits the upstanding blade to be forced into close contact with the proximate face of the rail head.

This switch point protector may be made of any suitable length but preferably in actual practice will be from 5 to 6 inches long.

An important advantage of this invention resides in the fact that the head piece is made to fit all sizes or classes of rails that are most used today. For instance, this head piece will fit a seventy, an eighty, ninety, one hundred or one hundred ten pound rail and the only change that will have to be made in using this device with these different classes of rails is to provide a wedge block of a different height for each class of rail to take care of the difference in height between an eighty, ninety, one hundred and one hundred and ten pound rail.

It is also the case that the head piece may be made to fit from 50 to 90 pound rails. In other words, 50 to 90 pound rails will require one size of head piece while another size of head piece is adapted to fit rails from 70 to 110 pounds. In other devices known to me of the same general character, it is necessary to have a different sized guard for each different sized rail which requires a large number of parts to be carried in stock. It further requires that if this guard is made of expensive and wear resisting material that each of these various sizes must be made of this expensive material. This is entirely done away with in my invention because the head piece itself need be made in only two sizes to suit rails from 58 to 110 pounds, whereas the relatively cheap malleable castings of the wedge block may be made in various heights to suit the different heights of the several different pound rails.

The blade 15 of each head piece 14 will have as much or more steel in it as is in the first six inches of the switch point C. This enables the blade to wear almost as long as the switch point will for when the point wears back or off from six to twelve inches, it is no longer used and is scrapped. With my device, the blade alone wears and the only replacement necessary is to replace an old or worn out head piece with a new head piece.

My device when completed is relatively light, it is readily installed and is extremely economical in actual service.

It is to be noted that the head piece 14 is not apertured for the passage of any bolts and that there are no inwardly projecting flanges on this head piece nor is this head piece unnecessarily thick and that it only extends downward a fraction of the distance between the tread surface of the rail A and the base *b* of the rail.

Thus this head piece is relatively light in weight and requires a relatively small amount of material to form it, thus reducing the cost of making this head piece of high grade manganese steel. The head piece may be readily cast or rolled. The aperture for the bolt or bolts is disposed entirely through the wedge block 10 and this wedge block does not have to be highly finished so that the cost of the wedge block is reduced over other forms of guard device known to me wherein a supporting block for the guard is used.

While I have illustrated one bolt as passing through the wedge block 10, it will be understood that it is within the per view of my invention to use more than one bolt if desirable but in actual practice I have found that one bolt is amply sufficient in view of the wedging action secured.

I am aware of the fact that guard or protector devices of this character have been made and used wherein a deflector member has been provided having a plurality of inclined surfaces, the deflector member being shiftable to place any one of these inclined surfaces in service or operative position with relation to the rail. In such case the deflector member is of relatively large size so that it extends from the upper surface of the head of the rail nearly to the beveled face of the base flange *b* and, therefore, if made of manganese steel is relatively costly. Furthermore, it is rendered costly by the fact that it is held in position in engagement with the rail not by any wedging action whatsoever, but by bolts which must pass through the deflector member proper as well as through the supporting block therefor, thus requiring that the deflector member shall be cored when cast.

Further, in this form of device, the deflector member is supported entirely by the bolts passing through it so that it does not wedge in its place and if the bolt breaks or becomes loose, the deflector member will either fall out or become loose and, of course, if it becomes loose, it will constitute a dangerous obstruction. My deflector member, which is constituted by the part 14, when supported by the block 10 cannot get out of place even though the bolt break or become loose.

It is because the bolt passes through the supporting or wedging block and does not pass through the head piece that it is possible to use the same head piece with various weights or sizes of rails and it is because in all other devices known to me of this charac-

ter, the bolt passes through what may be termed the head piece as well as through the support, where the support and head piece are made separately, that it is necessary to change not only the height of the supporting block or support but also change the size of the head piece.

While I have illustrated certain relatively minor details of construction and arrangements of parts, of course, I do not wish to be limited to such minor details except in so far as they are stated in the accompanying claims.

I claim:

1. A railway switch point protector including a head piece having two longitudinally and vertically rounded surfaces for diverting the flange of a railway wheel from the tapering end of a switch point, and means for wedging the same between the head and base of a railway rail in advance of a switch point, such means enabling either of the rounded surfaces to be placed in operative position without removing the remainder of the device.

2. A railway switch point protector including a head piece having two longitudinally and vertically rounded blades for deflecting the flange of a railway wheel from the tapering end of a switch point, and a wedge block formed at its upper edge to bear against the adjacent edge of the head piece and at its lower edge against the base of the rail, and a bolt passing through the wedge block and adapted to pass through the web of the rail the wedge block being spaced from the rail and being disposed exteriorly to the head piece whereby said wedge block may be adjusted inward to wedge the head piece upward against the head of the rail.

3. A railway switch point guard including a head piece formed with two offset oppositely projecting deflecting blades, each longitudinally and vertically rounded, and a wedge block to support the head piece formed at its upper edge to bear against the adjacent face of the head piece, and at its lower edge to have wedging engagement with the base of a rail, and means whereby the wedge block may be engaged with a rail.

4. A railway switch point guard including a head piece formed with two offset oppositely projecting deflecting blades, each longitudinally and vertically rounded, and a wedge block formed at its lower edge to wedge against the base of the rail, the upper edge of the wedge block being adapted to have engagement with and to support the head piece and hold it against the side and under face of a rail head, the inner face of the wedge block adjacent its upper edge being recessed to conform to and partially receive the depending blade.

5. A railway switch point protector embodying a head piece having two offset oppo-

sitely projecting deflecting blades each longitudinally and vertically rounded, each blade having a relatively flat inner surface both vertically and longitudinally, the outer surface of each blade tapering toward its ends and upward toward the ends of the blade, and a wedge block formed at its lower edge to bear against and have wedging engagement with the base flange of a rail and having its upper edge face downwardly and inwardly inclined whereby to support the head piece with its blades extending respectively upward and inward and downward and outward, the inner face of the wedge block adjacent its upper edge being recessed to accommodate the downward and outward inclination of the dependent blade, the wedge block having an aperture for a bolt.

6. The combination with a railway rail and a switch point, of a guard disposed in advance of the switch point including a head piece and a supporting block, the head piece resting upon the upper end of the supporting block and having a longitudinally and vertically rounded outer surface, the inner face of the supporting block being spaced from the web of the rail, the lower edge of the supporting block being beveled to fit the inclination of the upper surface of the rail base, and a bolt passing through the supporting block and rail and being disposed below the lower edge of the head piece.

7. The combination with a railway switch point and a main rail, of a guard mounted on the main rail including a head piece and a supporting block, the head piece resting upon the upper edge of the supporting block and being formed with a blade which has a longitudinally and vertically rounded outer surface, the head piece having a portion extending downward against the inner surface of the upper portion of the supporting block, the face of the end piece confronting the upper edge face of the supporting block being interdigitated therewith, and a bolt passing through the supporting block and through the web of the rail, the supporting block being at all times spaced from the web of the rail whereby it may be drawn inward by the bolt and have wedging engagement with the rail.

8. The combination with a switch point and a main rail, of a guard disposed in advance of the switch point, and including a head piece and a supporting block, the supporting block resting on the base of the rail and the head piece resting on top of the supporting block, the head piece having a longitudinally and vertically tapering outer surface, and a bolt passing through the supporting block and through the web of the rail, said bolt being disposed below the lower edge of the head piece.

9. The combination with a railway rail, of

a switch point guard mounted thereon including a head piece and a wedge block, the head piece being formed to provide two offset oppositely projecting deflecting blades, each longitudinally and vertically rounded, the wedge block being formed at its upper end to bear against the adjacent face of the head piece, with one of said blades projecting upward and the other blade projecting downward and bearing against the inside face of the wedge block, the lower edge of the wedge block being beveled to fit against the upper beveled face of the rail base, and a bolt passing through the wedge block and through the flange of the rail, each of said blades being recessed on its edge face to extend over the bolt.

In testimony whereof I hereunto affix my signature.
